UNITED STATES PATENT OFFICE

149,139

DESIGN FOR A MAN'S ATHLETIC SHOE OR
SIMILAR ARTICLE

Ralph A. Parker, Melrose, Mass.

Application November 9, 1946, Serial No. 134,641

Term of patent 14 years

(Cl. D7—7)

To all whom it may concern:

Be it known that I, Ralph A. Parker, a citizen of the United States of America, residing in Melrose, in the county of Middlesex and Commonwealth of Massachusetts, have invented a new, original, and ornamental Design for a Man's Athletic Shoe or Similar Article, of which the following is a specification, reference being had to the accompanying drawing, forming a part thereof.

Fig. 1 is a plan view of a man's athletic shoe, showing my new design;

Fig. 2 is a side elevational view thereof; and

Fig. 3 is a side elevational view of the opposite side shown in Fig. 2.

The dominant feature of the design resides in the side panels, contrasting in appearance with the quarter and vamp of the shoe and which collectively constitute substantially the entire top of the shoe, except for the eyelet stays, and which

extend forwardly from the back stay and taper to acute points located respectively at opposite sides of the shoe just to the rear of its toe portion.

I claim:

The ornamental design for a man's athletic shoe or similar article, substantially as shown and described.

RALPH A. PARKER.
